UNITED STATES PATENT OFFICE.

HENRY EARL ROSS, OF MILWAUKEE, WISCONSIN, ASSIGNOR TO UNITED SHOE MACHINERY CORPORATION, OF PATERSON, NEW JERSEY, A CORPORATION OF NEW JERSEY.

LASTING MACHINE.

Application filed June 24, 1925. Serial No. 39,267.

To all whom it may concern:

Be it known that I, HENRY E. Ross, a citizen of the United States, residing at Milwaukee, in the county of Milwaukee and State of Wisconsin, have invented certain Improvements in Lasting Machines, of which the following description, in connection with the accompanying drawings, is a specification, like reference characters on the drawings indicating like parts in the several figures.

This invention relates to lasting machines, and more particularly to end-lasting mechanism such as utilized, for example, in lasting the toes of shoes. The invention is here illustrated in its application to a bed lasting machine of the same general type as that shown and described in United States Letters Patent No. 1,284,870, granted on Nov. 12, 1918, upon an application of Matthias Brock, although the invention in various novel aspects is not limited to machines of that particular type.

It is a well-known fact that, as shoes that are made on so-called crooked lasts are positioned in machines of the above-mentioned type, the opposite side faces of the toe portion of each last are both inclined toward the front or toward the rear of the machine, that is, toward or away from the operator, the direction of the incline depending upon whether the shoe is a right shoe or a left shoe. In order that the toe-embracing wipers in their upward or upwiping movement shall bear with effective pressure upon the upper at both sides of the toe, and in order that the wipers at the end of the upwiping operation shall be positioned with their wiping edges in proper relation to the edge of the shoe bottom to begin the overwiping operation, machines such as shown in the above-mentioned patent include manually adjustable controlling mechanism acting automatically in the upwiping operation to impose to the toe wipers a predetermined movement laterally of the shoe relatively to their vertically moving support, so that their upwiping movement is actually on an incline corresponding substantially to the incline of the sides of the toe end of the last. In order to provide for properly adjusting the toe wiper controlling mechanism for right and left shoes respectively without special attention on the part of the operator, there

was further provided, in accordance with the invention disclosed in Patent No. 1,390,755, granted on Sept. 13, 1921, upon an application of Matthias Brock, a connection between this controlling mechanism and the heel-lasting mechanism which, in machines of the type illustrated, is positioned by the operator at equal distances on opposite sides of a central or intermediate position in the machine for operating respectively upon right and left shoes made on crooked lasts. When the machine is to operate upon shoes made on straight lasts the heel-lasting mechanism occupies a central position, and accordingly the mechanism controlling the toe wipers is so positioned as not to impart to the wipers any lateral movement in the upwiping operation.

While conditions requiring a lateral movement of the toe wipers such as above mentioned are more pronounced in shoes that are made on crooked lasts, which comprise, of course, the major portion of all shoes, it is nevertheless true that straight lasts of certain styles present, in some degree, conditions which likewise render it desirable that the toe wipers in the upwiping operation have a component of movement laterally of the shoe and in opposite directions respectively for right and left shoes. The present invention provides convenient and effective means for accomplishing this result. The construction shown comprises novel means adapted to be operated independently of the movement of the heel-lasting mechanism, for example when the latter is in a central position, to set or adjust the mechanism which effects the lateral movement of the toe wipers so as to cause the wipers to have such lateral movement in operating upon shoes made on straight lasts. The construction shown further comprises conveniently operable means for reversing the direction of lateral movement of the wipers for right and left shoes respectively and for insuring equal extent of lateral movement of the wipers in operating upon right and left shoes.

The features of the invention will now be more particularly described by reference to the accompanying drawings and thereafter pointed out in the claims.

In the drawings, Fig. 1 is a plan view of a bed-lasting ma-

- chine of the type shown in the patents above mentioned with the present invention embodied therein, parts being broken away to show what lies beneath:
- 5 Fig. 2 is a front elevation of a portion of the toe-lasting mechanism;
- 10 Fig. 3 is a perspective view, with parts broken away, of a portion of the mechanism for effecting and controlling lateral movement of the toe wipers;
- 15 Fig. 4 is a view partly in elevation and partly in section illustrating the relation of the toe wipers to the last;
- 20 Fig. 5 is a fragmentary perspective view, with parts broken away, showing a portion of the novel controlling mechanism provided for the purposes of the present invention with the parts in a different position than in Fig. 1;
- 25 Fig. 6 is a plan view in greater detail of a portion of the controlling mechanism shown in Fig. 5;
- 30 Fig. 7 is a view partly in elevation and partly in section, on a smaller scale, of the controlling mechanism shown in Fig. 5, and
- 35 Figs. 8 and 9 are views showing in greater detail a portion of the mechanism shown in Fig. 5 as viewed from opposite sides respectively.
- 40 As more fully shown and described in the prior patents mentioned, the machine is provided with shoe-positioning means comprising a heel pin 2 which engages the last in its spindle hole and a toe rest 4 upon which the forepart of the shoe is supported. For operating upon the heel end of the shoe there is provided heel-lasting mechanism, comprising the usual heel band and wipers 6 mounted on a heel carriage 8 which carries also the heel pin 2 and is pivoted to swing laterally about a vertical axis 10, the carriage 8 being supported for swinging movement upon a track 12 by means of rolls 14. In operating upon shoes made on crooked lasts the operator swings the heel carriage 8 in one direction to position it for operating upon a right shoe and in the opposite direction to position it for operating upon a left shoe. To insure that the heel-lasting mechanism, in operating upon right and left shoes respectively, will be positioned at equal distances from a central or intermediate position, the machine is provided with a pair of stops 16 which are adjustable toward and from each other by means of a right and left screw 18, and the heel carriage 8 has a latch 20 for engaging these stops to limit the movement of the carriage in the different directions. By turning the screw 18 the operator may determine the angular relation of the heel-lasting mechanism to the longitudinal median line of the machine, which will be the same whether the mechanism is positioned for operating upon a right shoe or upon a left shoe. In the machine shown in

Fig. 1 the stops 16 are set to position the heel-lasting mechanism centrally for operating upon right or left shoes that are made on straight lasts.

The toe-lasting mechanism comprises toe-embracing wipers 22 and also, as herein shown, a toe band 24, although the invention is not limited to a construction including a toe band. The wipers and the toe band are movable upwardly and downwardly by means of a vertically movable support 26 (Fig. 2) which is operated by a treadle 28 (Fig. 1), and it will be understood that by means of the treadle the operator raises the wipers 22 while holding them closed about the toe of the shoe by means of a hand lever 30 to upwipe the upper about the toe. The wipers 22 and the toe band 24 are carried by a slide 32 which is mounted on the support 26 for movement laterally of the shoe. The slide 32 is provided at the rear with lugs 34 (Fig. 3) which have bearings for a cylindrical sleeve 36 and have openings below the sleeve. The sleeve 36 is provided with a rectangular slot extending lengthwise thereof to receive a normally stationary square shaft 38, and secured to the sleeve between the lugs 34 is a block 40 which is provided with a slot 42 in line with the slot in the sleeve to serve as a downward extension of the latter. The square shaft 38 is mounted at its ends in bearings so that it may be turned to position it with its opposite sides either vertical or at any desired inclination to the vertical, the sleeve 36 and the block 40 turning with the shaft. It will thus be evident that if the shaft 38 is positioned with its opposite sides vertical, no movement laterally of the shoe will be imparted to the slide 32 and the toe wipers when the wiper support 26 is moved upwardly, but if the shaft is turned so that its opposite sides are at an inclination to the vertical, a proportional movement laterally of the shoe will be imparted to the slide 32 and the wipers by the action of the shaft as a guide on the sleeve 36 and the block 40.

In operating upon shoes made on right and left crooked lasts the degree of inclination of the sides of the shaft 38, and therefore the extent of lateral movement imparted to the toe wipers in the upwiping operation, is determined by the position of the laterally movable heel carriage 8, and for this purpose the shaft 38 is connected to the heel carriage. Fast on the shaft 38 is a slotted lever arm 44 which is connected to a similarly slotted arm of a lever 46, this lever having operative connection at its lower end with a pin 48 on one arm of a horizontal lever 50, and the latter being connected by means of a link 52 to the heel carriage 8 through mechanism hereinafter described. The connection between the arm 44 and the lever 46 comprises a block 54

which is adjustable along the slot in the arm 44 and has pivoted thereon a second block 56 which is movable along the slot in the lever arm 46. By this mechanism the shaft 38 is adjusted initially so that its opposite sides are vertical when the heel carriage 8 occupies a central position, thus insuring that the toe wipers will have lateral movements of equal extent in operating upon right and left shoes when the heel carriage is moved to positions at equal distances from its central position.

For purposes of the present invention there is provided means for operating the horizontal lever 50 to position the shaft 38 with its opposite sides at an inclination to the vertical when the heel carriage or the heel-lasting mechanism is in its intermediate or central position, and thus to cause the toe wipers to receive movement laterally of the shoe in operating upon shoes made on straight lasts, without interfering with the normal use of the machine as hereinbefore described in operating upon shoes made on crooked lasts. To this end, the connection between the link 52 and the heel carriage 8 comprises a slide 58 which may be secured centrally on the heel carriage to move therewith or may be moved relatively to the heel carriage when the latter is latched in its central position. The heel carriage has depending therefrom a bracket 60 in which is a curved guideway 62 for the slide 58, the latter being provided on one side with lugs 64 which support the slide at that side upon the top edge of the bracket in any position of the slide. Under the guideway 62 the bracket 60 is provided with a pair of straight guideways 66 in angular relation to each other, and mounted in the guideways 66 are slides 68 which are adjustable toward or from each other by means of right and left threaded screws 70 which are connected together by a universal joint 72 so that both are operated by turning one of them. The screws 70 are journaled at their outer ends in bearings formed in the bracket 60, and one of them is provided at 74 with a squared end for turning it. The slides 68 carry upwardly projecting pins 76 which extend into the path of movement of the slide 58 and serve as stops to limit movement of the latter in opposite directions. When the machine is to operate upon shoes made on crooked lasts, the slides 68 are so adjusted that the pins 76 hold the slide 58 between them in a central position on the heel carriage, as illustrated in Figs. 5, 6 and 7, so that the link 52 is connected to the heel carriage at a point substantially midway between the opposite sides of the latter, as in the prior Brock machine of Patent No. 1,890,755.

When the machine is to operate upon shoes made on straight lasts, with the heel

carriage 8 in a central position, as illustrated in Fig. 1, the slides 68 are so adjusted as to permit such movement of the slide 58 between the pins 76 as is necessary in order to adjust the square shaft 38 to impart to the toe wipers the proper extent of lateral movement in operating on right or left shoes. Movement of the slide 58 in opposite directions between the pins 76 is effected by means of a curved lever arm 78 which, for convenience, is pivoted to swing about the same axis 10 as the heel carriage and is provided with a handle 80 in a convenient position for the operator to reach it at all times. It is desirable that the slide 58 be locked at either limit of its movement between the pins 76, and for this purpose the slide has pivoted thereon a pair of latches 82 arranged to engage the respective pins and pulled downwardly toward the pins by springs 84. For controlling these latches there is mounted on the slide 58, on the same pivot pin to which the link 52 is connected, a sleeve 86 having recesses in its opposite sides, as shown in Figs. 8 and 9, and in these recesses the sleeve is provided with downwardly facing cams 88 and 90. Extending from the latch 82 which is nearest the front of the machine is a curved arm 92 the end of which projects into one of the recesses in the sleeve 86 and is engaged by the cam 88. Extending from the other latch 82 is an arm 94 which has on its end a lateral projection 96 engaged by the cam 90. The cams 88 and 90 are so arranged that when the sleeve 86 is in an intermediate position both the latches 82 are held out of engagement with the pins 76, as illustrated in Fig. 7. When the sleeve 86 is turned in one direction from its intermediate position, it releases one of the latches 82 to permit it to engage the corresponding pin 76, while continuing to hold the other latch upwardly out of position to engage its pin. When the sleeve is turned in the opposite direction it releases the last-named latch, while holding the first one in an elevated position. Movement of the sleeve 86 in one direction is limited by engagement of a shoulder 98 thereon with the end of the arm 92, and movement of the sleeve in the opposite direction is limited by engagement of a shoulder 100 thereon with the projection 96 on the arm 94. The sleeve 86 is controlled by the lever 78 which, for this purpose, is connected to a crank arm 102 projecting from the sleeve.

When the machine is to operate upon shoes that are made on straight lasts the heel carriage 8 is latched in central position, as shown in Fig. 1. If the shape of the last makes it desirable to impart lateral movement to the toe wipers in the upwiping operation, the operator adjusts the slides 68 far enough apart to permit such movement

of the slide 58 and the connected parts of the wiper-controlling mechanism as is necessary to give the wipers the lateral movement required. The adjustment for any particular style of shoe may be conveniently determined by trial. To position the parts for operating upon a left shoe, as illustrated, the operator swings the lever 78 forwardly until the slide 58 engages that pin 76 which is nearest the front of the machine. In this movement of the lever 78 the sleeve 86 is first turned so as to release the latch 82 which is nearest the front of the machine, while maintaining the other latch in an elevated position, and when the shoulder 98 on the sleeve engages the end of the arm 92 the lever 78 becomes effective to move the slide 58 forwardly until the foremost latch 82 snaps over the corresponding pin 76. When it is desired to position the parts for operating upon a right shoe, the operator swings the lever 78 in the opposite direction, and in this swinging movement of the lever the front latch 82 is lifted from the pin 76 and the other latch is released to permit it to engage its pin, and the slide 58 is moved to its limit in the opposite direction. If the machine is to operate upon shoes made on crooked lasts the operator adjusts the slides 68 toward each other until the slide 58 is clamped by the pins 76 in a central position on the heel carriage, as illustrated in Fig. 7. Movement of the heel carriage will then adjust the parts of the toe wiper-controlling mechanism in the same manner as heretofore.

Having described the invention, what I claim as new and desire to secure by Letters Patent of the United States is:—

40 1. A machine of the class described having, in combination, shoe-positioning means, toe-embracing wipers, means for imparting to said wipers unwiping movement heightwise of the toe of a shoe including a component of movement laterally of the shoe, heel-lasting mechanism movable laterally to different positions for operating respectively upon right and left shoes made on crooked lasts and arranged to occupy an intermediate position for operating upon shoes made on straight lasts, mechanism for determining by the lateral movement of the heel-lasting mechanism the direction and extent of the lateral movement of the toe wipers in operating upon shoes made on crooked lasts, and mechanism movable independently of the heel-lasting mechanism when the latter is in its intermediate position for determining the direction and extent of the lateral movement of the toe wipers in operating upon shoes made on straight lasts.

60 2. A machine of the class described having, in combination, shoe-positioning means, toe-embracing wipers, means for imparting to said wipers upwiping movement height-

wise of the toe of a shoe including a component of movement laterally of the shoe, heel-lasting mechanism movable laterally to different positions for operating respectively upon right and left shoes made on crooked lasts and arranged to occupy an intermediate position for operating upon shoes made on straight lasts, means controlled by the heel-lasting mechanism for causing the toe wipers to receive lateral movements of the same extent but in different directions in operating respectively upon right and left shoes made on crooked lasts, and means controlled independently of the heel-lasting mechanism for causing the toe wipers to receive lateral movements of the same extent but in different directions in operating respectively upon right and left shoes made on straight lasts.

3. A machine of the class described having, in combination, shoe-positioning means, toe-embracing wipers, means for imparting to said wipers upwiping movement heightwise of the toe of a shoe, heel-lasting mechanism movable laterally to different positions for operating respectively upon right and left shoes made on crooked lasts and arranged to occupy an intermediate position for operating upon shoes made on straight lasts, a device arranged to be set by the lateral movement of the heel-lasting mechanism to cause the toe wipers in the upwiping operation to have a component of movement laterally of shoes made on crooked lasts, and mechanism for setting said device independently of movement of the heel-lasting mechanism to cause the toe wipers to have a component of lateral movement in operating upon shoes made on straight lasts.

4. A machine of the class described having, in combination, shoe-positioning means, toe-embracing wipers, means for imparting to said wipers unwiping movement heightwise of the toe of a shoe, heel-lasting mechanism movable laterally to different positions for operating respectively upon right and left shoes made on crooked lasts and arranged to occupy an intermediate position for operating upon shoes made on straight lasts, a device arranged to be set by the lateral movement of the heel-lasting mechanism to cause the toe wipers in the upwiping operation to have a component of movement laterally of each shoe of the same extent but in different directions respectively in operating upon right and left shoes made on crooked lasts, and mechanism for setting said device independently of movement of the heel-lasting mechanism to cause the toe wipers to have a component of lateral movement of the same extent but in different directions respectively in operating upon right and left shoes made on straight lasts.

5. A machine of the class described having, in combination, shoe-positioning means,

toe-embracing wipers, means for imparting to said wipers upwiping movement heightwise of the toe of a shoe, heel-lasting mechanism including a heel carriage movable laterally to different positions for operating respectively upon right and left shoes made on crooked lasts and arranged to occupy an intermediate position for operating upon shoes made on straight lasts, a device arranged to be set by the lateral movement of the heel-lasting mechanism to cause the toe wipers in the upwiping operation to have a component of movement laterally of shoes made on crooked lasts, and mechanism movably mounted on the heel carriage for setting said device to cause the toe wipers to have a component of lateral movement in operating upon shoes made on straight lasts.

6. A machine of the class described having, in combination, shoe-positioning means, toe-embracing wipers, means for imparting to said wipers upwiping movement heightwise of the toe of a shoe, heel-lasting mechanism including a heel carriage movable laterally to different positions for operating respectively upon right and left shoes made on crooked lasts and arranged to occupy an intermediate position for operating upon shoes made on straight lasts, and a device connected to the heel carriage and arranged to be set thereby to cause the toe wipers in the upwiping operation to have a component of movement laterally of shoes made on crooked lasts, the connections between said device and the heel carriage comprising a slide movable on the heel carriage when the latter is in its intermediate position for setting said device to cause the toe wipers to have a component of lateral movement in operating upon shoes made on straight lasts.

7. A machine of the class described having, in combination, shoe-positioning means, toe-embracing wipers, means for imparting to said wipers upwiping movement heightwise of the toe of a shoe, heel-lasting mechanism including a heel carriage movable laterally to different positions for operating respectively upon right and left shoes made on crooked lasts and arranged to occupy an intermediate position for operating upon shoes made on straight lasts, a device for imparting to the toe wipers in the upwiping operation a movement laterally of the shoe, connections between said device and the heel carriage for setting said device by the lateral movements of the heel carriage to cause the toe wipers to receive lateral movements in different directions respectively in operating upon right and left shoes made on crooked lasts, said connections including a member movably mounted on the heel carriage for setting said device when the heel carriage is in its intermediate position, and stops on the heel carriage for determining different positions of

said member to cause the toe wipers to receive lateral movements of the same extent but in different directions in operating upon right and left shoes made on straight lasts.

8. A machine of the class described having, in combination, shoe-positioning means, heel-lasting mechanism arranged to occupy a central position in the machine in operating upon right and left shoes made on straight lasts, toe-embracing wipers, means for imparting to said wipers upwiping movement heightwise of the toe of each shoe, controlling mechanism comprising a guide shiftable between different positions for imparting to said toe wipers in the upwiping operation movement laterally of the shoe in opposite directions respectively for right and left shoes, means for shifting said guide while the heel-lasting mechanism occupies its central position, and means for determining symmetrically opposite positions of said guide to insure that the lateral movements of the toe wipers in the opposite directions will be of the same extent.

9. A machine of the class described having, in combination, shoe-positioning means, heel-lasting mechanism arranged to occupy a central position in the machine in operating upon right and left shoes made on straight lasts, toe-embracing wipers, means for imparting to said wipers upwiping movement heightwise of the toe of each shoe, controlling mechanism comprising a guide shiftable between different positions for imparting to said toe wipers in the upwiping operation movement laterally of the shoe in opposite directions respectively for right and left shoes, a member slidably movable in opposite directions for shifting said guide while the heel-lasting mechanism occupies its central position, and adjustable stops arranged to limit the movements of said member and to insure that the lateral movements of the wipers in the opposite directions will be of the same extent.

10. A machine of the class described having, in combination, shoe-positioning means, heel-lasting mechanism including a heel carriage arranged to occupy a central position in the machine in operating upon right and left shoes made on straight lasts, toe-embracing wipers, means for imparting to said wipers upwiping movement heightwise of the toe of each shoe, controlling mechanism comprising a guide shiftable between different positions for imparting to said toe wipers in the upwiping operation movements laterally of the shoe in opposite directions respectively for right and left shoes, and means movably mounted on the heel carriage for shifting said guide while the heel carriage occupies its central position.

11. A machine of the class described having, in combination, shoe-positioning means,

heel-lasting mechanism including a heel carriage arranged to occupy a central position in the machine in operating upon right and left shoes made on straight lasts, toe-embracing wipers, means for imparting to said wipers upwiping movement heightwise of the toe of each shoe, controlling mechanism comprising a guide shiftable between different positions for imparting to said toe wipers in the upwiping operation movements laterally of the shoe in opposite directions respectively for right and left shoes, a member connected to said guide and mounted on the heel carriage for movements

in opposite directions to position the guide for operating respectively upon right and left shoes, and stops on the heel carriage for limiting the opposite movements of said member, said stops being adjustable in unison toward or from each other to vary the extent of lateral movement of the toe wipers while insuring that the lateral movements of the wipers in the opposite directions will be of the same extent. 15

In testimony whereof I have signed my name to this specification. 20 25

HENRY EARL ROSS.

Certificate of Correction.

It is hereby certified that in Letters Patent No. 1,583,012, granted May 4, 1926, upon the application of Henry Earl Ross, of Milwaukee, Wisconsin, for an improvement in "Lasting Machines," errors appear in the printed specification requiring correction as follows: Page 4, lines 43 and 108, claims 1 and 4, respectively, for "unwiping" read *upwiping*; and that the said Letters Patent should be read with these corrections therein that the same may conform to the record of the case in the Patent Office.

Signed and sealed this 19th day of October, A. D. 1926.

[SEAL.]

WM. A. KINNAN,
Acting Commissioner of Patents.
